CLAIM

The ornamental design for cosmetic compact, as shown and described.

DESCRIPTION

FIG. 1 is a top perspective view of a cosmetic compact, in an open position showing my new design;

FIG. 2 is a top plan view, shown in a closed position;

FIG. 3 is a bottom plan view thereof;

FIG. 4 is a front elevational view thereof;

FIG. 5 is a rear elevational view thereof; and

FIG. 6 is a left side elevational view thereof, the side opposite being a mirror image of the side shown.

FIG. 1

FIG. 3

FIG. 4

FIG. 5
